UNITED STATES PATENT OFFICE.

HENRY E. WASHBURN, OF PLYMOUTH, MASSACHUSETTS.

DESIGN FOR A HANDLE FOR SPOONS.

SPECIFICATION forming part of Design No. 24,535, dated August 13, 1895.

Application filed June 25, 1895. Serial No. 554,069. Term of patent 7 years.

To all whom it may concern:

Be it known that I, HENRY E. WASHBURN, a citizen of the United States, residing at Plymouth, in the county of Plymouth, State of Massachusetts, have invented a new and original Design for a Handle for Spoons, Forks, or Similar Articles, of which the following is a specification, reference being had to the accompanying drawing, forming part thereof.

10 The drawing represents in top view a handle for spoons, forks, or similar articles, showing my design.

15 The leading feature of my design for a handle for spoons consists in the representation in outline and relief of John Alden and Priscilla in Puritan costume upon the handle near its outer end, the remaining narrow portion of the handle having scroll-like ornamental edges. The figure *a* of John Alden
20 supports a musket upon one shoulder, and

the companion figure *b*, Priscilla, carries a book, both figures being depicted in outline and relief. The remaining narrow portion of the handle *c* is provided with scroll-like ornamentation along its edges.

25 The bowl *c'* of the spoon is shown in full lines, and in dotted lines I have indicated the tines of a fork.

I claim—

20 The design for a handle for spoons, forks and similar articles, substantially as herein shown and described.

In testimony whereof I have signed my name to this specification in the presence of two subscribing witnesses.

HENRY E. WASHBURN.
